DESIGN FOR A HEAT EXCHANGE UNIT

Frederick L. Anderson and John M. Baeza,
San Francisco, Calif.

Application July 23, 1940, Serial No. 93,876

Term of patent 14 years

To all whom it may concern:

Be it known that we, Frederick L. Anderson, a citizen of the United States, and John M. Baeza, a national of Spain, residing in the city and county of San Francisco, and State of California, have invented a new, original, and ornamental Design for a Heat Exchange Unit, of which the following is a specification, reference being had to the accompanying drawing forming a part thereof.

Figure 1 is a side elevational view of a heat exchange unit embodying our new design;

Figure 2 is an end elevational view thereof; and

Figure 3 is a cross-sectional view thereof on the line 3—3 of Figure 1, looking in the direction of the arrows.

We claim:

The ornamental design for a heat exchange unit, substantially as shown.

FREDERICK L. ANDERSON.
JOHN M. BAEZA.
